United States Patent Office

Des. 207,867
Patented June 6, 1967

207,867

LIGHT FIXTURE

Myron F. Pettengill, Hendersonville, N.C., assignor to
General Electric Company, a corporation of New York

Filed July 21, 1966, Ser. No. 3,167

Term of patent 14 years

(Cl. D48—23)

Fig. 3.

Fig. 4.

Fig. 5.

Fig. 6.

FIGURE 1 is a top plan view of a light fixture embodying my new design;

FIGURE 2 is an elevational view thereof;

FIGURE 3 is a bottom plan view thereof;

FIGURE 4 is a perspective view of a modified form of the light fixture shown in FIGURES 1-3;

FIGURE 5 is a front elevational view of the FIGURE 4 light fixture; and

FIGURE 6 is a bottom plan view thereof.

I claim:

The ornamental design for a light fixture, as shown.
